KARL BÖHLE, OF ESSEN, GERMANY, ASSIGNOR TO FRIED. KRUPP AKTIENGESELLSCHAFT, OF ESSEN-ON-THE-RUHR, GERMANY.

PRESS FOR PRODUCING HOLLOW BODIES.

Application filed December 6, 1920. Serial No. 428,645.

To all whom it may concern:

Be it known that I, KARL BÖHLE, residing at Essen, Germany, a citizen of the German Republic, have invented a certain new and 5 useful Improvement in Presses for Producing Hollow Bodies, of which the following is a specification.

The present invention relates to presses for producing hollow bodies, a blanking or 10 shearing punch being provided for the cutting of the stock to its correct size before the actual pressing takes place. The main object of the invention is to provide a 15 shearing or blanking punch, adapted to be locked to the die and to embrace the press punch in such a manner that it can serve as a stripping member for the finished stock when the press punch is moved rearwardly.

20 This new construction also provides several other advantages, which will be fully described in the following.

One embodiment of the invention is 25 shown in the drawing, illustrating a press for manufacturing hollow bodies of circular shape.

Fig. 1 shows in longitudinal section certain parts of the press;

30 Figs. 2 to 4 are views similar to Fig. 1, showing the same parts in different positions; and

Fig. 5 is a partial side view seen from the left, corresponding to Figs. 3 and 4.

The hollow cylindrical press punch A is 35 rigidly connected with a plate B, on the under side of which followers D of angular shape are hinged to the plate by means of screw bolts C. Bolts C', provided with nuts e' at the upper end, run with play 40 through the plate B. These bolts carry at their lower ends a shearing or blanking punch E of T-shaped cross-section. With only slight play the horizontal portion e² of the shearing punch E embraces the press 45 punch A, and the inner lower edge e⁴ of the vertical arm e³ of the blanking punch E is constructed as a cutting or shearing edge.

The die F is provided with a projection f' on its upper side towards the blanking punch, the outer edge f² of which is shaped 50 as a cutting edge which is intended to cooperate with the cutting edge e⁴ of the blanking punch E. Two ring-sector shaped ribs f⁷ and f⁸ (see Fig. 5) are moreover

connected by means of screws f⁶, to the die 55 F, these ribs being situated in the same plane. In the two diagonally oppositely located grooves formed between the ribs f⁷ and f⁸ a knife f³, having a V-shaped edge, is inserted for the purpose that they shall 60 cooperate with the notches e⁶ on the lower side of the vertical arm e³ of the blanking punch E (see Fig. 5). Furthermore, the pegs f⁴ are connected with the die F, which pegs project through holes e⁵ in the blanking punch E with small play, each of which being provided with a small hole f⁵. These holes f⁵ are intended to receive the "follower" pins G, and are arranged in such a 65 manner that they lie above the upper surface 70 of the blanking punch E, with the press in the position in which the knives f³ have entered the notches e⁶ (see Figs. 3, 4 and 5).

Before operation the followers D are 75 swung inwards against the longitudinal axis of the press until they have the position shown in Figs. 1 and 2, wherein they couple together the press punch A with the blanking punch E through the intermediary 80 of the plate B, when the press punch goes down. The stock (sheet H) previously warmed to red heat and intended for the manufacture of the hollow body, is now placed on the die F and the press set in 85 action. The blanking punch E then first arrives in contact with the sheet H (Fig. 1), whereupon, during further travel downwards of the press punch A, the cutting edges e⁴ and f² come into action, shearing off the 90 outer portion of the stock sheet H. The sheared off portion of the sheet falls down and lies on the knives f³. Towards the end of the downward movement of the blanking die E the knives f³ will function with the 95 grooves e⁶ of the vertical arm e³ of the blanking die (see Fig. 2), so that the cut off portion h' (see Fig. 5) of the stock sheet is cut in half and may consequently be readily removed.

100 The press is now stopped and the followers D swung outwards, whereupon the coupling between the press punch A and the blanking punch E is disconnected.

The press is then again set in motion. 105 The blanking punch remains stationary, but the press punch A continues its travel and presses down the stock plate H in the

die, whereupon the hollow body to be produced is formed in well-known manner from the stock plate.

- Upon completion of the actual pressing operation the press is again stopped, whereupon the pins G are inserted in the holes f^5 of the pegs f^4 . The blanking punch E is thus secured to the die F. The parts then have the relative positions shown in Fig. 3.
- 10 During the upstroke of the press punch, the finished pressed plate adhering to the press punch then strikes against the horizontal portion e^2 of the blanking die E (see Fig. 4); so that during continued movement upward of the press punch it will be pushed off the latter. As soon as this has taken place, the press is again stopped and the pins G removed from the holes f^5 . Towards the end of the return stroke of the press punch the plate B abuts against the nuts e^7 of the bolts e^6 and carries the blanking punch E into its initial position through the intermediary of the bolts. When the press stamp A has arrived in its initial position the followers D will again be swung inwards and the press is then again ready to start.

Claims.

1. A press for producing hollow bodies comprising a die, a press punch, a blanking punch having blanking means and embracing the press punch for stripping the finished stock off the press punch during the

rearward stroke, means for locking the blanking punch to the die and means for locking the blanking punch to the press punch in a readily detachable manner. 35

2. A press for producing hollow bodies comprising a die, a press punch, a blanking punch, and knives mounted on said die 40 and arranged in the path of the blanking punch, said knives contacting with said blanking punch to cut the outer portion (previously sheared off from the stock) into several pieces. 45

3. A press for producing hollow bodies comprising a die, a press punch, a blanking punch having blanking means and embracing the press punch for stripping the finished stock off the press punch during the 50 rearward stroke, followers connected to the press punch, said followers being adapted to be swung outwards and to couple together the press punch and the blanking punch in the direction of the pressing stroke 55 of the press punch, and means for locking the blanking punch to the die in a readily detachable manner.

The foregoing specification signed at Essen, Germany, this 26th day of August, 60 1920.

KARL BÖHLE.
